FIREPLACE

Edwin L. McElheny, R.R. 1, Nappanee, Ind. 46550

Filed Jan. 15, 1970, Ser. No. 20,940

Term of patent 14 years

Int. Cl. D23—03

U.S. Cl. D23—97

FIG. 1

FIG. 3

FIG. 2

FIG. 1 is a perspective view of a fireplace embodying the present design;

FIG. 2 is a front elevational view thereof on a reduced scale, the flue and screen mesh being fragmentarily shown for convenience of illustration; and

FIG. 3 is a side elevational view thereof on a reduced scale, the flue being fragmentarily shown for convenience of illustration.

The top of the fireplace is flat and unornamented.

I claim:

The ornamental design for the fireplace, as shown and described.
